United States Patent Office

Des. 186,484
Patented Oct. 27, 1959

186,484

WRITING INSTRUMENT DESK SET BASE

Donald W. Doman, Janesville, Wis., assignor to The Parker Pen Company, Janesville, Wis., a corporation of Wisconsin

Application September 20, 1957, Serial No. 47,788

Term of patent 14 years

(Cl. D74—1)

FIG. 1

FIG. 2

FIG. 3

FIG. 4

Fig. 1 is a top perspective view of a writing instrument desk set base showing my new design;

Fig. 2 is a top plan view thereof;

Fig. 3 is an edge elevational view thereof, the side opposite thereto being similar in appearance; and

Fig. 4 is an end elevational view thereof.

I claim:

The ornamental design for a writing instrument desk set base, substantially as shown and described.
